US0D1106484S

(12) **United States Design Patent** (10) Patent No.: **US D1,106,484 S**
(45) Date of Patent: ** Dec. 16, 2025

(54) **SAMPLE DETECTOR**

(71) Applicant: **Zhejiang Orient Gene Biotech Co., Ltd**, Zhejiang (CN)

(72) Inventors: **Siyu Lei**, Zhejiang (CN); **Jianqiu Fang**, Zhejiang (CN)

(73) Assignee: **ZHEJIANG ORIENT GENE BIOTECH CO., LTD**, Zhejiang (CN)

(**) Term: **15 Years**

(21) Appl. No.: **29/912,157**

(22) Filed: **Sep. 14, 2023**

(30) **Foreign Application Priority Data**

Jul. 26, 2023 (CN) 202330471150.0

CLAIM

The ornamental design for a sample detector as shown and described.

DESCRIPTION

FIG. 1 is a perspective view of a sample detector showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof.

The broken lines depict portions of the sample detector that form no part of the claimed design.

1 Claim, 8 Drawing Sheets
